US00D767485S

(12) **United States Design Patent** (10) **Patent No.:** **US D767,485 S**
(45) **Date of Patent:** **** Sep. 27, 2016**

(54) BATTERY CASE	5,001,772 A	3/1991	Holcomb et al.
(71) Applicant: Mophie, Inc. , Tustin, CA (US)	D322,719 S	12/1991	Jayez
(72) Inventors: Nguyen To , Corona, CA (US); Ming Chiao Chiang , Alhambra, CA (US); Denny Tsai , Temple City, CA (US); Fanpeng Zeng , Shenzhen (CN)	D327,868 S	7/1992	Oka
(73) Assignee: mophie, inc. , Tustin, CA (US)	5,360,108 A	11/1994	Alagia
(**) Term: 14 Years	5,368,159 A	11/1994	Doria
(21) Appl. No.: 29/523,211	5,383,091 A	1/1995	Snell
(22) Filed: Apr. 7, 2015	5,386,084 A	1/1995	Risko
(51) LOC (10) Cl. 13-02	5,508,123 A	4/1996	Fan
(52) U.S. Cl.	D372,896 S	8/1996	Nagele et al.
